UNITED STATES PATENT OFFICE.

ROBERT L. BAILEY, OF DETROIT, MICHIGAN, ASSIGNOR OF SEVEN-TENTHS TO AUSTIN F. BURDICK AND ONE-TENTH TO JAY W. SLAUGHTER, BOTH OF LANSING, MICHIGAN.

ROTARY MOTOR.

Application filed January 8, 1923. Serial No. 611,299.

My invention relates to motors of the rotary type and its purposes are to make a device that shall be as nearly as possible perfectly balanced, capable of running at a very 5 high speed and free from excessive friction.

I attain these purposes by the means shown in the accompanying drawings in which Fig. 1 is a front elevation of my device, the front cover being removed to show 10 the internal mechanism. Fig. 2 is a vertical section of one form of my device along the line 1—1 of Fig. 1. Figs. 3 and 4 are details showing modified constructions, and will be more fully explained hereafter.

15 While I have shown and described my invention as applied to a vapor motor of the explosive type, I wish it to be understood that it may be used also as a steam engine or as a pump without departing from my invention. This will be readily evident from the method of its operation as hereafter explained.

20 My device consists primarily of an outer rotor 1 which is substantially in the shape of a hollow cylinder. This cylinder revolves on a fixed axis 2 on suitable bearings 3, 4, 5, and 6. The operation of the bearings 4 and 5 will be more fully explained hereafter. An internal rotor 7 is mounted to revolve 25 on a fixed axis 8 eccentrically positioned with reference to the axis 2 of the outer rotor. The rotor 7 revolves on a suitable bearing 9. By this construction, as appears from the drawings, the internal rotor revolves inside of the external, but nearer to one side 30 than to the other, forming by this means, an expansion space which will be more fully explained hereafter, in connection with the operation. The internal and external rotors 35 revolve synchronously. This effect may be produced in various ways without departing from my invention. In the method I have shown, circular recesses 10 are formed in the rotor 7 and pins 11 are inserted in the ring 15 of the external rotor in such position 40 as to engage with the internal circumferences of the recesses 10. By this means the internal and external rotors are compelled to revolve together but each is permitted to 45 revolve freely about its own axis. The radius of the recesses 10 is equal to the sum of the distances between the axes of the two rotors and the radius of the pins 11. In the form 50 shown in Figs. 1 and 2, slots 13 are formed

in the rotor 7 of a depth sufficient to receive 55 the vanes 14 and permit the necessary play of those vanes as will be more fully explained hereafter. When used in a four stroke cycle gas engine of the explosive type as shown in the drawings, the vanes may be 60 any odd number. A projecting ring 15 is formed on the interior surface of the cover 12. This ring is provided with as many plane faces as the number of vanes 14, and the inner edge of each of the vanes 14 is continuously in contact with the corresponding plane surface of the ring 15. Correlated plane surfaces 16 are formed on the internal surface of the external rotor and the outside edge of each of the vanes 14 is in continuous 65 engagement with its corresponding surface 16. By this means the space between the internal and external rotors is divided into as many non-communicating chambers as there are vanes. A valve disk 17 is mounted between the internal rotor and the rear cover 70 18 of the external rotor. This revolves on the bearings 4 and 6 and is thus concentric with the external rotor. These bearings thus serve a double purpose, serving as bearings 75 both for the external rotor and the valve disk 17. The valve disk is provided with a plurality of inlet ports 19 and exhaust ports 20. When used, as shown, as an explosive 80 gas engine of the four-stroke cycle type, the 85 number of each kind of ports will be one-half of one more than the number of the vanes 14; thus, in the drawings, there are 90 nine of these vanes and five inlet and exhaust ports. In the modification shown in 95 Fig. 4, the inlet and exhaust ports in the disk 17 are combined into one, but the action is precisely the same. For reasons that will be more fully explained hereafter, each of 100 the ports 19 and 20 is divided by partitions 21 so that in every case the openings 22 will be narrower than the thickness of the vanes 14. The disk 17 is driven from the external 105 rotor 1 by a system of gears 23, 24, 25, and 26, revolving, two about the shaft 2 and the other two about a stationary stud 27 attached to the frame 28 of the engine. The ratio between the various gears constituting this system is such that, while the disk 17 is making a number of complete revolutions equal to the number of vanes 14, the rotors 1 and 7 will have made one more revolution than that number. For example, in the con-

struction, as shown by the drawings, when the disk 17 has made nine revolutions, the rotors 1 and 7 will have made ten, the ratio of the gear combination, therefore, being 5 that of nine to ten. By this means, the rotors will gain on the disk an amount equal to one of the expansion chambers, during each revolution of the disk. An inlet port 32 is formed in the rear end 18 of the external rotor in each of the chambers formed by the vanes 14. Gas is supplied to the inlet port 32 by passages 29 formed in the end 18. These ports are indicated by dotted lines in Fig. 1. Leakage of gas around the 15 disk 17 is prevented by packing rings 33, and around the vanes 15, by packing segments 34 which extend between the vanes. The bearing 5 permits the necessary relative motion between the disk 17 and the external 20 rotor. Suitable packings 35 are provided to prevent leakage of air around the shaft 2. A spark plug 36 of any approved type is provided for each of the chambers formed by the vanes 14. These spark plugs are connected by suitable wiring to a distributor 37, that revolves with the rotor. I am aware that this distributor is not new, and it forms 25 no part of my invention.

The front end of the device is supported 30 by a shaft 39 which passes through a bearing 38 and from which power is transmitted. The device is oiled by a tube 40 which extends through the shaft 2 into the cavity between the internal and external rotors and 35 is supplied with oil by any suitable means.

As already stated, I have shown and described the method of providing for the radial motion of the vanes 14 by mounting them in slots 13 in the internal rotor. I, at 40 present, consider this to be preferable but any other method of producing the same effect may be employed without departing from my invention. For example, the vanes 14 may be hinged to the outer rotor as in 45 Fig. 4 and slide between packing strips 41 or that arrangement may be reversed as shown in Fig. 3, it only being essential to my invention that the vanes 14 shall at all 50 times prevent any communication or leakage whatever from one chamber to the other.

For convenience in describing the operation of the device, I have marked the chambers A, B, C, D, E, F, G, H, and J. Referring to Fig. 1 of the drawings, the chamber B is now just at the point when the intake port 32 will start to open. It will be noted that the exhaust port 20 in the valve disk 17 has just passed beyond the exhaust port 31 in the end 18 and the inlet port 19 55 is just entering in the inlet port 32 in that chamber. The motion is the direction indicated by the arrow. As the chamber B continues to move about the circle, when it has advanced 80°, it will reach the position 60 shown at D and the ports will then have

the relation to each other shown in that chamber, namely, the two inlet ports will be nearly fully registered. This effect is brought about by the gain of the rotors on the disk which has been already described. 70 This produces an additional effect which will be referred to further on. As it continues to revolve to 160°, the ports reach the condition shown in chamber F. It will be noted that the inlet ports on the disk and 75 end are separating from each other; the exhaust port, however, still remaining closed. As it passes onward to 240°, the condition will then be as shown at H. In this position both exhaust and inlet ports 80 are closed. This is more clearly shown in this chamber by breaking away a portion of the disk 17 to show the relative condition of the ports in the rear end 18. As the revolution still continues to 320°, the ports 85 reach the position shown at A in this chamber. It will be noted that no port in the disk 17 is now in this chamber. The inlet and exhaust ports are both closed and the compression is approximately complete. 90 This is chosen as the firing point to allow for the spark advance, well known to be necessary in engines of this type. As the revolution still continues to 400° or 40° on the second revolution, the position C is 95 reached, the expansion has taken place and there is still no port in the chamber, thus, through all of the intense heat formed by the explosion and the high pressure caused by the pressure and compression of the gases 100 combined, no port will be in a situation to be injured. It will be noted also that owing to the axes of the two rotors not coinciding with each other, the chamber is now increasing in size, therefore giving opportunity for expansion of the gases, and acting on the two axes to produce the rotation, the effect being identically the same as with the action of a crank of the same length as the distance between the two axes. 105 As the revolution continues to 120° of the second revolution, the condition in chamber E is reached, the expansion has still continued and both ports are still closed, but the exhaust port 20 in this chamber is 110 approaching the exhaust port 31 in the end. As the revolution continues to 200° of the second revolution, the exhaust port in the end 18 has overtaken the exhaust port in the disk and the exhaust has commenced. 115 The condition in this chamber also illustrates the importance of the partitions 21 since the partitions 21 in the inlet port 19 now act to prevent the passage of gases from chamber G to chamber H. The same thing 120 is true with the exhaust ports between chambers E and F. When the revolution has continued to 280°, the condition shown at chamber J is reached. The exhaust is still continuing, but the exhaust port in the end 125 130

is beginning to pass beyond the exhaust port in the disk and the port is, therefore, closing. When the revolution has continued to 360° of the second revolution, the ports are again in their original position and ready to start on a second cycle. I referred above to an additional effect which was produced by the fact that the axes of the two rotors are not concentric. As the rotors revolve, 10 the vanes 14 are at all times substantially radial to the inner rotor. Therefore, during the first quarter of the revolution starting from the point B, they would be rising with reference to the exterior rotor and the outer edge of the vanes 14 would be moving along the plane surface 16 of the chamber in which the vane is located until at 90° the vane would reach its highest point. When 180° is reached, the centers are again in line and 15 the position of the vane with reference to the exterior rotor is precisely the same as it was at the beginning of the revolution. As the revolution continues, when 270° is reached, the vane has moved along its plane 20 surface to the farthest point in the opposite direction and is beginning to return, and when the revolution is completed, again reaches the original position. The effect of this action during the first quarter of the 25 revolution during the intake stroke is to slightly retard the increase of the chamber in capacity, while the valve is slightly opened and during the second quarter of this stroke the opposite effect is produced. 30 The same is true during the third and fourth quarters and also during the firing and exhaust strokes. This effect is especially important during the firing stroke because it 35 holds the pressure during a greater period of time.

The action of the modification shown in Figs. 3 and 4 is precisely the same as in Figs. 1 and 2. However, the vane necessarily does not travel along the surface of the exterior rotor, but the effect to increase and diminish the size of the chamber is brought about by the change in the angle of the vane with reference to the radius of the internal rotor.

It does not seem necessary to describe the action of the recesses 10 and pins 11 at any considerable length. It is evident that, as the rotors revolve, the effect of the distance between the radii of the two rotors is continually keeping the pins 11 pressed against the internal surface of the recesses 10. The rotors will, therefore, be held continually in the same relation to each other while each chamber will move about the axis of the exterior rotor.

I claim as my invention and desire to secure by Letters Patent:

1. In combination, in a device of the character described, an external rotor; an internal rotor mounted within said external

rotor on an axis non-concentric with that of said external rotor and operatively connected to said external rotor so as to revolve synchronously therewith and in the same direction; a plurality of vanes movably mounted 70 in one of said rotors and movably engaged with the other so as to divide the space between said rotors into a plurality of non-communicating chambers, and a valve disk mounted between said rotors and so connected thereto as to revolve in the same direction with an angular velocity bearing a predetermined ratio to that of said rotors. 75

2. In combination, in a device of the character described, an external rotor; an 80 internal rotor mounted within said external rotor on an axis non-concentric with that of said external rotor and operatively connected to said external rotor so as to revolve synchronously therewith and in the same direction; a plurality of vanes movably mounted 85 in one of said rotors and movably engaged with the other so as to divide the space between said rotors into a plurality of non-communicating chambers, and a valve disk 90 mounted between said rotors and operatively connected thereto as to revolve in the same direction at such an angular velocity as that said external rotor will gain upon said disk a distance equal to one of said 95 chambers in a complete revolution of said disk.

3. In combination, in a device of the character described, an external rotor; an internal rotor mounted within said external 100 rotor on an axis non-concentric with that of said external rotor and operatively connected to said external rotor so as to revolve synchronously therewith and in the same direction; a plurality of vanes movably mounted 105 in one of said rotors and movably engaged with the other so as to divide the space between said rotors into a plurality of non-communicating chambers, and a valve disk 110 mounted between said rotors and operatively connected thereto so as to revolve in the same direction with an angular velocity bearing a predetermined ratio to that of said rotors and provided with a plurality of 115 ports adapted to co-act with corresponding ports in said exterior rotor.

4. In combination, in a device of the character described, an external rotor; an internal rotor mounted within said external 120 rotor on an axis non-concentric with that of said external rotor and operatively connected to said external rotor so as to revolve synchronously therewith and in the same direction; a plurality of vanes movably mounted 125 in one of said rotors and movably engaged with the other so as to divide the space between said rotors into a plurality of non-communicating chambers; a valve disk mounted between said rotors and operatively connected thereto so as to revolve in 130

the same direction with an angular velocity bearing a predetermined ratio to that of said rotors and provided with a plurality of subdivided ports adapted to co-act with corresponding ports in said exterior rotor.

5. In combination, in a device of the character described, an external rotor; an internal rotor mounted within said external rotor on an axis non-concentric with that of 10 said external rotor and operatively connected to said external rotor so as to revolve synchronously therewith and in the same direction; a plurality of vanes movably mounted in one of said rotors and movably engaged 15 with the other so as to divide the space between said rotors into a plurality of non-communicating chambers, and a valve disk mounted between said rotors and operatively connected thereto as to revolve in the 20 same direction at such an angular velocity as that said external rotor will gain upon said disk a distance equal to one of said chambers in a complete revolution of said disk and provided with a plurality of ports 25 adapted to co-act with corresponding ports in said exterior rotor.

6. In combination, in a device of the character described, an external rotor; an internal rotor mounted within said external rotor on an axis non-concentric with that 30 of said external rotor and operatively connected to said external rotor so as to revolve synchronously therewith and in the same direction; a plurality of vanes movably 35 mounted in one of said rotors and movably engaged with the other so as to divide the space between said rotors into a plurality of non-communicating chambers, and a valve disk mounted between said rotors and 40 operatively connected thereto as to revolve in the same direction at such an angular velocity as that said external rotor will gain upon said disk a distance equal to one of said chambers in a complete revolution of 45 said disk and provided with a plurality of subdivided ports adapted to co-act with corresponding ports in said exterior rotor.

7. In combination, in a device of the character described, an external rotor; an internal rotor mounted within said external rotor on an axis non-concentric with that 50 of said external rotor and operatively connected to said external rotor so as to revolve synchronously therewith and in the same direction; a plurality of vanes movably 55 mounted in one of said rotors and movably engaged with the other so as to divide the space between said rotors into a plurality of non-communicating chambers, and a valve 60 disk mounted between said rotors and operatively connected thereto as to revolve in the same direction at such an angular velocity as that said external rotor will gain upon said disk a distance equal to one of 65 said chambers in a complete revolution of

said disk and provided with a plurality of subdivided ports adapted to co-act with corresponding ports in said exterior rotor, and means for preventing leakage from one chamber to another.

8. The combination with an internal combustion engine provided with a plurality of combustion chambers and adapted to revolve about a shaft, each of said combustion chambers being provided with a port, of a valve 75 for said engine also mounted to revolve about said shaft in the same direction as said engine with an angular velocity bearing a fixed ratio to the angular velocity of said engine.

9. The combination with an internal combustion engine provided with a plurality of combustion chambers and adapted to revolve about a shaft, each of said combustion chambers being provided with a port, of a valve 85 for said engine also mounted to revolve about said shaft, and connected to said engine so as to revolve in the same direction as said engine with an angular velocity bearing a fixed ratio to the angular velocity of 90 said engine.

10. The combination with an internal combustion engine provided with a plurality of combustion chambers and adapted to revolve about a shaft, each of said combustion chambers being provided with a port, of a valve 95 for said engine, provided with an inlet and an exhaust port, and also mounted to revolve about said shaft, and connected to said engine so as to revolve in the same 100 direction as said engine with an angular velocity bearing a fixed ratio to the angular velocity of said engine.

11. The combination with an internal combustion engine provided with a plurality of 105 combustion chambers and adapted to revolve about a shaft, each of said combustion chambers being provided with a port, of a valve for said engine, provided with a plurality of inlet and exhaust ports, and also mounted to 110 revolve about said shaft, and connected to said engine so as to revolve in the same direction as said engine with an angular velocity bearing a fixed ratio to the angular velocity of said engine.

12. The combination with an internal combustion engine provided with a plurality of combustion chambers and adapted to revolve about a shaft, each of said combustion chambers being provided with a port, of a valve 120 for said engine, provided with a plurality of inlet and exhaust ports, the number of said inlet and exhaust ports bearing a fixed ratio to the number of said combustion chambers, said valve being also 125 mounted to revolve about said shaft, and connected to said engine so as to revolve in the same direction as said engine with an angular velocity bearing a fixed ratio to the angular velocity of said engine.

13. The combustion with an internal combustion engine provided with a plurality of combustion chambers and adapted to revolve about a shaft, each of said combustion chambers being provided with a port, of a valve for said engine, provided with a plurality of inlet and exhaust ports, adapted to co-act with said first mentioned ports, the number of said inlet and exhaust ports bearing a fixed ratio to the number of said combustion chambers, said valve being also mounted to revolve about said shaft, and connected to said engine so as to revolve in the same direction as said engine with an angular velocity bearing a fixed ratio to the angular velocity of said engine. 10 15

ROBERT L. BAILEY.
